(57) CLAIM

I claim the ornamental design for a merchandise display pocket, as shown and described.

DESCRIPTION

FIG. 1 is a perspective view of a merchandise display pocket showing my new design;

FIG. 2 is a rear perspective view thereof;

FIG. 3 is a top view thereof;

FIG. 4 is a left side view thereof;

FIG. 5 is a frontal view thereof;

FIG. 6 is a right side view thereof; and

FIG. 7 is a bottom view thereof; and,

FIG. 8 is a rear view thereof.

The broken line showing in FIG. 3 is for environmental purposes only and form no part of the claimed design.
